Primary Examiner — Nathan M Johnston

(57) CLAIM

The ornamental design for a wall-mounted bathroom shelf, as shown and described.

DESCRIPTION

1. Wall-mounted bathroom shelf

1.1 : Perspective

1.2 : Perspective

1.3 : Front

1.4 : Back

1.5 : Left

1.6 : Right

1.7 : Top

1.8 : Bottom

1.9 : Enlarged

The parts shown by means of broken lines in the reproductions are not part of the claimed design; fig. 1.9 is the enlarged view of the portion taken at line 9 in fig. 1.1; the dash dot dash lines in fig. 1.1, 1.9 and the number "9" in fig. 1.1 are for the purpose of depicting the cut line of the enlarged view and form no part of the claim.
